LIFESAVING HEADGEAR

Dickran Sebouh, New York, N. Y.

Application June 23, 1942, Serial No. 448,129

2 Claims. (Cl. 128—145)

My invention relates to life saving devices for preventing persons from drowning, and has for its object to provide a device of the indicated type constructed in a novel manner to enable persons to remain safely in the water for indefinite periods without swimming.

The invention contemplates further the provision of a novel life saving device which when worn by a person enables the latter to breathe normally and without effort even though the face of the wearer of said device may be completely submerged in water.

The invention further has for its object to provide a novel life saving device which may be used alone or in conjunction with other approved devices such as conventional life preservers, life jackets and the like, and in any case supplies the wearer immersed in water with air in adequate amounts for breathing purposes as along as may be required.

Other objects will appear from the description hereinafter and the features of novelty will be pointed out in the claims.

In the accompanying drawing, which illustrates an example of the invention without defining its limits,

Fig. 1 is a front elevation of the novel device showing the same in use;

Fig. 2 is a side elevation of the novel device in place upon a person submerged in water;

Fig. 3 is a fragmentary side view of the novel device with a part broken away;

Fig. 4 is a fragmentary front view of the device in section;

Fig. 5 is an enlarged fragmentary sectional view of the upper portion of the device;

Fig. 6 is a perspective sectional view of a hand pump which may be included in the device, and

Fig. 7 is an enlarged cross-section on the line 7—7 of Fig. 5.

In detail, my device consists of four separate units which when assembled will look as shown in Fig. 1. The parts forming the first unit, viz., the mask 1, the cap 2, the tubes 3, 4, and 5, the fitting 6 and the loops 7 are permanently attached together, in their respective places, for instance by waterproof cementing. The entire first unit is put on and taken off as one piece of wearing apparel. The mask 1 is somewhat round in shape and extends outward from the face and forms a small chamber around the mouth and the nose. The mask 1 may be made of light plastic material and then cemented on the cap 2, or it may be made of rubber and form an integral part of the cap 2. In the latter case

the walls of the mask section preferably are of greater thickness and heavier than the adjoining cap section (see Figs. 3 and 4) in order to prevent the mask from collapsing over the mouth and the nose under the pressure of the water, thereby making it impossible or very difficult to breathe. The mask 1 is provided with three, preferably round perforations a, b, and c, into which fit the tubes 3, 4 and 5 respectively, the latter being permanently attached to said mask 1 in a manner shown in Fig. 4. The other ends of the tubes 3 and 4 are similarly attached to a suitable fitting 6, while the free end of the tube 5 is detachably connected to a hand pump 8 for the purpose to be more fully set forth herein-after.

The cap section 2 is made of highly elastic material, such as rubber, which clings firmly to the head of the wearer thereby making the device waterproof and also more easily adjusted to various size heads. Loops 7 suitably attached to the cap 2 are provided for clamping the tubes 3 and 4 to said cap 2 in more or less fixed position thereon and for preventing said tubes from swinging about. The two apertures 9 on the cap, for the eyes, may be left uncovered exposing the eyes to the water. This will not in any way affect the purpose of my device. However, for the sake of better vision, comfort and for the protection of the eyes, the cap 2 may be provided with a pair of goggles 10 (Fig. 2) formed as an integral part thereof in registry with the apertures 9.

The fitting 6 may be also made of elastic material, such as rubber, and may be made as a separate piece and then cemented in place on the top part of the cap 2 or said fitting 6 may be molded with the cap in one piece. The walls and the base of the fitting 6, Fig. 5, are heavy and strong enough to maintain an air-pipe 12 of four or five feet in length, in an erect position on the cap 2 so as to project above the surface of the water when the device is in use and yet flexible enough to permit said pipe 12 to yield to the body movements of the wearer and to the splash of water or impact of a wave hitting said pipe 12, and thereby prevent excessive strain being transmitted to the head of the wearer. Acting as a shock absorber, the corrugation 13 will contribute further help in this respect. On the inner surface of the walls of the fitting 6, extending for about an inch, is a spiral groove into which is threaded the threaded end of the air-pipe 12, so as to snugly fit said fitting 6. A free space about one half or five eighths of an inch

deep is left between the bottom of the fitting 6 and the inner end of the pipe 12 to permit the circulation of the air between the air-pipe or tube 12 and the tubes 3 and 4 leading from the mask 1 as shown in Fig. 5.

The second unit of my device comprises the very light but tough plastic pipe or tube 12, four or five feet long and having an inside diameter of about one and a quarter inches and a wall thickness of about one thirty-seconds of an inch. The lower end of this pipe is threaded and fits tightly into the fitting 6 as mentioned above. The other end of the tube 12 is extended slightly outward to form an annular flange 14. The interior of this pipe or tube is divided into two equal and independent channels by a partition 15 (Fig. 7) running along its entire length and parallel to its longitudinal axis. With this arrangement the exhaled air passes outwardly through the pipe 12 along one side of the partition 15, while at the same time fresh atmospheric air passes inwardly through the pipe 12 along the opposite side of said partition 15. In other words, because of the fact that the exhaled air is lighter than the fresh atmospheric air, said exhaled air rises in the pipe 12 to one side of the partition 15 as stated, and thereby develops a true convection current in said pipe 12 which removes the exhalation products and supplies fresh air for inhalation to the wearer of the device.

The third unit, made of an elastic material, such as rubber, is the topmost hollow terminal piece 16 having a central section and two tubular sections suspended freely therefrom in the air with their open ends facing downward as shown in Figs. 1, 2 and 5. The central section is forced down over the top end of the air-pipe 12 and is secured in place by the flange 14 at the end of the air-pipe 12. The small extension 17 on the inside of this third unit, by resting on the upper end of the partition 15, prevents the terminal piece 16 from sliding down on the pipe or tube 12 and closing the air passage.

No matter what position the air-pipe 12 assumes, viz, perpendicular or tipping forward, backward or sideward, the open ends of the flexible tubular sections of the terminal piece 16, suspended freely in the air, will always face downward due to the force of gravity. The air might be shut off, for an instant only, by a splash of water or a wave completely enveloping the terminal piece and the entire length of the air-pipe, but no water will run up against the force of gravity and enter thru the open ends of the terminal piece and thence into the air-pipe and the mask. It is only on very unusual occasions and by an unusual combination of successive swinging motions of the air-pipe that a small amount of water might be forced into the open ends of the terminal piece and might reach the mask; and it is for this emergency only that the pump 8 has been introduced, as described below.

The fourth unit is a small hand pump 8 (Figs. 1 and 6), consisting of a hollow oval rubber bulb terminating at two of its opposite ends in the tubes 18 and 19, each tube being about three quarters of an inch long and each having an inside diameter of about one quarter of an inch. At the outermost end the edges of the tube 18 converge to a point inside the tube forming the valve 20 and closing the entrance into the bulb. The valve 21 is formed in the same way except that the edges of the tube 19 converge to close

the exit end of the bulb at a point outside the tube 19. Both of these valves 20, 21, operate in the same direction so that when the bulb 8 is squeezed the compressed air presses the valve 21 open and forces at the same time whatever

water that there is in the bulb 8, out thru the tube 22. As soon as the bulb is released the suction created inside the expanding bulb will cause the valve 20 to open, allowing any water which may have accumulated in the mask 1 and the tube 5 to enter the bulb and to be expelled from the bulb thru the tube 22 by the next compression of said bulb 8. Thus as soon as the wearer of this device feels any water in the mask he will be able to pump it out by the repeated alternate operation of compressing and releasing the rubber bulb. This pump unit, as stated once before, is included in my device only as an additional safety measure. It will not be necessary to operate it at all except on rare occasions. It can even be dispensed with when the device is to be used in calm waters.

This concludes the structural description of my device. Regarding its operation the following simple directions are explanatory.

First.—Screw the long plastic air-pipe 12, as far as it will go, into the fitting 6 located on the top of the cap 2.

Second.—Press the central part of the two-armed hollow terminal piece 16 over the top end of the air-pipe 12 and force it down as far as it will go.

Third.—Connect the rubber bulb with the free end of the small tube 5 protruding from the lower part of the mask 1 and see that it is securely in place.

Now the device is ready to wear. Put it on as you would a bathing cap and a mask. Adjust it well so that it clings snugly to the back of your head, to your face and under your chin, leaving no bulges or openings that will let water into the mask. If in a rough sea, water should enter the mask, the water may be removed by compressing and releasing the rubber bulb 8 until all the water is expelled from the mask. When swimming hold your head up.

In reference to swimming with my device the following final explanation seems to be in order.

As seen in Fig. 2, the air-pipe is installed in a slightly inclining position in order to have it at nearly the same angle with the plane of the surface of the water both in standing position and swimming position of the body, meaning that the uppermost end of the air-pipe will be as far above the surface of the water in swimming position as it is in the standing position because in swimming, excepting in using the crawl stroke, the head is raised upwards bringing the air-pipe to the position shown by the dotted lines in Fig. 2, which position, as far as the distance between the end of the air-pipe and the surface of the water is concerned, is approximately the same as the position of said pipe when the wearer is in an upright position in the water.

Having thus concluded the description of my invention I claim:

1. A life saving device to prevent drowning comprising a watertight mask, means for firmly securing said mask over the face of the wearer, a flexible fitting arranged to be positioned on the head of said wearer, a tube having its one end secured in said fitting and projecting upwardly therefrom above the level of the water in which said wearer is afloat, means at the free end of said tube for preventing free entry of water into

the same without interfering with the admission of air to the interior of said tube, air connections establishing communication between said tube and said mask, a partition extending lengthwise of said tube and dividing the interior thereof into two channels whereby a convection current is developed in said tube for supplying breathing air to the interior of said mask and for removing exhalation products therefrom to enable the wearer to breathe normally in water while completely submerged therein up to any depth not greater than that which enables the means at the free end of said tube to remain above the surface of said water, and a hand pump connected with said mask and operating at will to drain out incidental water accumulated therein.

2. The combination of a watertight mask, an air tube associated with said mask, means for firmly securing said mask over the face of the wearer and for maintaining said tube in an erect 20

position upon the head of the wearer, a device fitted upon the free end of said tube for preventing free entry of water into the same, said device comprising a central section and two tubular sections suspended freely therefrom by gravity, air connections establishing communication between said mask and said tube, means whereby free circulation of air through said air connections between the mask, air tube and atmosphere 10 is provided for supplying breathing air to and removing exhalation products from said mask to enable the wearer to breathe normally in water while completely submerged therein up to any depth not greater than that which permits the 15 open ends of said tubular sections to remain above the surface of said water, and a hand pump connected with said mask and operating at will to drain out incidental water accumulated therein.

DICKRAN SEBOUH.
